UNITED STATES PATENT OFFICE.

JOHN A. LIDBACK, OF PORTLAND, MAINE, ASSIGNOR OF ONE-HALF TO J. J. GERRISH, OF SAME PLACE.

RAILWAY-GATE.

SPECIFICATION forming part of Letters Patent No. 349,597, dated September 21, 1886.

Application filed March 10, 1886. Serial No. 194,744. (No model.)

To all whom it may concern:

Be it known that I, JOHN A. LIDBACK, of Portland, in the county of Cumberland and State of Maine, have invented a new and useful Improvement in Railway-Gates; and I do hereby declare that the following is a full, clear, and exact description of the same.

My invention relates to railway-gates of that class in which the gates swing vertically on posts and are operated through the medium of a liquid acting upon a piston moving in a cylinder and connected to the gate.

Heretofore a vertically-swinging gate has been shown as adapted to be lowered by hydraulic pressure by means of an open cylinder having a piston therein, with a pipe-connection between the piston and the forcing mechanism, the piston being connected to the gate by a pitman. My invention differs from this in having a closed cylinder with the piston contained therein and connections from the forcing mechanisms communicating with the cylinder above and below the piston, whereby the gate may be raised and lowered positively by the hydraulic pressure. As my cylinder is closed at both ends, I cannot have a pivoted piston-rod or pitman, as in the construction referred to, in order to permit necessary movement thereof in the raising and lowering of the gate, so I pivot my cylinder within the post and connect the piston-rod directly to the gate-arm, and the movement of the gate-bar rocks the cylinder back and forth upon its pivots. In order to introduce the liquid by which the piston is moved, conducting-passages are made through the trunnions of the cylinder, and are extended to enter into the cylinder at both ends above and below the piston. I have further sought to improve the details of construction of the apparatus for forcing the liquid by which the piston within the gate-post is operated. All the details of construction whereby these objects are secured are explained fully hereinafter, and are illustrated in the accompanying drawings, in which—

Figure 1 shows the gate-post in front elevation, with a part of the casing broken away to show the interior mechanism. Fig. 2 is a vertical section. Fig. 3 is a detached view of the cylinder, which is pivoted in the post. Fig. 4 is a section of the same, taken across the

drawings. Fig. 5 is a transverse section of the same. Fig. 6 is a side elevation of the hydraulic rams and the mechanism for operating them. Fig. 7 is an end elevation of the same. 55

In the drawings the swinging bar which constitutes the gate or obstruction to the railway is shown at L. The said bar is formed of the two parts L and L', converging and joined together at their upper ends, so as to 60 form a single bar in the usual manner. The bar is fixed to the shaft M, which turns on one side of a hollow post, A, set in a suitable position by the side of the railway and the street or highway which crosses the railway. Midway of the length of this shaft is set thereon a fixed arm, I, which extends into the space of the interior of the post, and has room therein to swing sufficiently to allow the gate to rise and fall through the arc of its movement. 70 Connected to the free end of this arm is the piston-rod k of the piston C in the cylinder B. This cylinder is pivoted upon trunnions on its lower end, working in bearings in the lower part of the cavity of the post, these bearings 75 being in line parallel with that of the shaft on which the gate turns. The cylinder and piston are designed to be operated by a liquid, either water or some practically incongealable liquid. The pivot allows the cylinder to oscillate with 80 the movement of the arm I as the gate is raised and lowered. The liquid is introduced into the cylinder below the piston C by a pipe, G, which communicates with a port, g', formed on the trunnion on one side and leading to the 85 interior through the lower cylinder-head. Liquid communication with the other end of the cylinder is through a pipe, G', which arrangement of these pipes is shown more clearly in Figs. 3 and 5. It will be observed that 90 when the force of liquid is applied to the upper side of the piston it draws down the arm I and raises the gate; but when the force is applied below it raises the arm I and lowers the gate. These operations are rendered easy 95 by counter-balance Q on the rear end of the gate.

The apparatus for transmitting motion by pressure upon the liquid medium is shown in Figs. 6 and 7. In Fig. 6 are shown four cylinders adapted to operate four gates at the same time, or two and two together. The cyl-

inders P are in line fixed underneath the bed-plate U. Standards T, set on this plate, support the shaft on which are the pinions X, by which the pistons are operated. One of the 5 pistons is shown Fig. 7 at 2. The others are the same. These pistons are connected to piston-rods passing through stuffing-boxes g. On the upper ends of these stuffing-boxes are rack-bars W, which gear into pinions X. The two 10 right-hand pinions X X of Fig. 6 are of the same sleeve, and move together and are held to the shaft by a clutch, z, so that the pistons may be operated in pairs or all four together, at the will of the operator. The shaft carries 15 on its outer end a gear-wheel, c, fixed thereto, which is operated by the pinion d and crank e. By turning this crank the pistons may be raised or lowered, and the liquid medium be forced down or up. The cylinders P are connected to the cylinders in the post by the pipes G G'. The pipe G is connected to the lower part of the cylinder P at R, and the pipe G' is connected to the same cylinder above the piston at r. Therefore when the pistons 2 are 20 depressed the piston C is forced up and the gate is lowered. It will be observed that by the described arrangement of the pipes the liquid is kept in readiness for action, for when the liquid is forced in below the piston C it forces 25 the liquid above it into the pipe G'', which is in communication with the upper part of the cylinder P, where a vacuum is being created, so that the liquid from the upper part of the chamber B is transferred to the upper part of 30 the chamber P, and the reverse takes place by 35 reverse movement of the piston 2. The pairs of cylinders P are connected to the posts on the same side of the railway, so that the gates on one side of the railway may be operated 40 independently of those on the other. Manifestly, on narrow roads where only one gate is used the cylinders will be used singly, instead of in pairs, and only two would be required for the transmission of the power applied to 45 the cranks.

It will be understood that the apparatus shown in Figs. 6 and 7 may be set at any desired distance from the gate, the pipes being led to the cylinders P from the cylinders in 50 the gate-posts, and the stations may be at such point that the attendant can readily observe the approach of trains, and thus may be enabled to act intelligently in raising and lowering the gates.

55 The gates are to be arranged in the same manner as such gates are ordinarily arranged—a pair on each side of the railway, each pair facing each other and adapted to descend and to obstruct the roadway. A cylinder is placed 60 in each post, and the pipes G G' of the gates on one side of the railway extend to a pair of cylinders, P P, whose pistons are connected to the gears and operate together, so that the gates upon one side may be operated independently of the others, as heretofore ex-

plained. The gate-posts have openings in one side, so that the cylinders are easily accessible for oiling or repairs. The working parts are all above ground, and, being within the posts, are protected perfectly.

70 It will be apparent that I may use in this apparatus any liquid or fluid medium; but a liquid capable of withstanding low temperature is preferable.

I claim as my invention—

1. In combination with a railway-gate pivoted upon a hollow post to swing in vertical plane, a closed liquid-cylinder pivoted within the hollow post, having its piston connected to an arm rigidly connected with the gate, and pipes leading into the cylinder above and below the piston, said pipes being connected with a suitable forcing mechanism, whereby the gate is operated positively both in raising and lowering, all substantially as described. 75

80 2. In combination with a gate pivoted upon a hollow post to swing in vertical plane, a closed liquid-cylinder pivoted within the hollow post to swing in a plane parallel with that of the gate, and having its piston-rod attached to an arm connected rigidly with the gate, and 85 passages for the liquid communicating with the interior of the cylinder above and below the piston, and connected also with mechanism for forcing the liquid and operating the gate, 90 substantially as described. 95

100 3. In combination with a vertically-swinging gate pivoted upon a hollow post, a closed cylinder pivoted within the hollow post to swing in a plane parallel with that of the gate, provided with passages through its trunnions, and having its piston-rod attached to an arm rigidly connected to the gate, and suitable pipes connecting the interior of the cylinder above and below the piston with suitable forcing 105 mechanism, all substantially as described.

110 4. In combination with pivoted gates adapted to be operated by hydraulic power, closed cylinders pivoted to swing within hollow posts provided with operating-pistons and inlet and exit passages, and a forcing mechanism consisting of a main shaft, pinions mounted thereon, and the toothed piston-rods, substantially as described.

115 5. In combination with pivoted gates adapted to be operated by hydraulic power, closed cylinders pivoted to swing within hollow posts provided with operating-pistons and inlet and exit passages, a forcing mechanism consisting of a main shaft, collars mounted thereon carrying pinions, and toothed piston-rods, and clutch mechanism, whereby the gates may be operated in pairs, substantially as described.

120 In testimony whereof I have signed my name to this specification in the presence of two sub- 125 scribing witnesses.

JOHN A. LIDBACK.
